UNITED STATES PATENT OFFICE.

ALFRED DREYLING, OF MAURER TOWNSHIP, MIDDLESEX COUNTY, NEW JERSEY,
ASSIGNOR OF TWENTY-FIVE ONE-HUNDREDTHS TO WILLIAM C. LOCKE, OF
STAMFORD, CONNECTICUT.

REINFORCED SHOE.

1,305,782.

Specification of Letters Patent. Patented June 3, 1919.

Application filed October 28, 1918. Serial No. 260,001.

To all whom it may concern:

Be it known that I, ALFRED DREYLING, a citizen of the United States, residing at Maurer township, in the county of Middlesex and State of New Jersey, have invented new and useful Improvements in Reinforced Shoes, of which the following is a specification.

This invention relates to shoes, and more particularly to shoes formed of canvas, and designed to serve as a substitute for leather in the manufacture of shoes for work purposes and the like. One object is to provide a shoe, the upper of which is formed of an outer layer of reinforced canvas, and an inner layer of canvas cemented to the outer layer, the sole and heel being formed of reinforced layers of canvas, and other layers of canvas of the usual commercial quality. A still further object is to provide means for reinforcing the arch of the shoe, in addition to the reinforcement of the upper, sole and heel in the manner indicated.

With the foregoing and other objects in view, the invention consists in the novel construction, combination and arrangement of elements hereinafter described and claimed.

In the drawings,

Figure 1 illustrates a shoe in elevation, fragmentary portions of the reinforcement being shown.

Fig. 2 is a view in vertical section.

Fig. 3 is a bottom plan view, with portions broken away.

In carrying out my invention I form an upper 10 of an outer reinforced layer 12 and an inner layer 14 of a commercial type of canvas of suitable quality.

The outer layer may be of ten ounce canvas, reinforced with strands of wire designated 15, this wire being of copper, brass, aluminum, or other metal. The wire strands 15 are interwoven with the cotton threads designated 16, the various strands being meshed as indicated, two strands of cotton threads being placed side by side, and then a strand of wire, followed by two additional strands of cotton. This type of mesh

extends in both directions, the transverse 50 and longitudinal strands corresponding, so far as their relative positions are concerned. The wire strands are of a gage corresponding with the cotton strands of the canvas.

The inner layer 14 of water-proof cloth 55 of any suitable commercial type is cemented to the outer layer, a canvas strip 18 being secured along the edges where the eyelets are formed. The toe portion is reinforced with a layer of canvas in the manner indicated in Fig. 1.

The sole 20 is of six ply, the three layers next to the upper being of ten ounce canvas cemented together, and the three lower layers being of reinforced canvas formed of cotton 65 and wire mesh in the manner previously indicated. These layers are cemented together and then sewed, rows of stitches extending across the entire sole. The arch of the shoe is reinforced by means of a steel spring designated 70 24.

The heel is preferably formed of 12 layers, the three lower layers being of reinforced canvas.

What is claimed is:

1. In a shoe, an upper formed of a plurality of thicknesses of material, the outer thickness comprising a layer formed of fiber and of wire, the fiber and wire being interwoven, and a sole and heel for the shoe, certain of the layers of said sole and heel being reinforced with wire. 75

2. In a shoe, an upper formed of a plurality of layers of flexible material cemented together, one of the layers comprising threads 80 of fibrous material interwoven with wire strands, and a sole and heel for the shoe.

3. In a shoe, an upper formed of inner and outer layers cemented together, the outer layer comprising a fabric formed of strands 85 of fibrous material, interwoven with strands of wire, a plurality of fiber strands being located between each two strands of the warp and weft strands of wire, and a sole and heel for the shoe. 90

4. In a shoe, an upper formed of a plurality of layers of material, one of which is formed of fiber interwoven with wire, flexi- 95

ble means for reinforcing the edges of the upper adjacent to the opening of the tongue, and a sole formed of a plurality of layers of flexible material and a plurality of layers formed of fiber interwoven with wire, the wire extending in the direction of the warp and in the direction of the weft, the layers

of flexible material and the layers within which the wire mesh is incorporated being stitched across substantially the entire surface, and means for reinforcing the arch of the shoe.

In testimony whereof I affix my signature.

ALFRED DREYLING.
